TABLE

Walter Franklin Breen, Lancaster, and Moses Brendle Good, Ephrata Township, Lancaster County, Pa., assignors to Hamilton Watch Company, Lancaster, Pa.

Application May 14, 1943, Serial No. 486,956

3 Claims. (Cl. 311—84)

This invention relates to tables and more particularly to that type of table which has folding legs and if generally used with large numbers of similar tables and where it is often necessary to store said tables in a compact space.

In factories or organizations where a cafeteria is often used for other purposes and it is very desirable to remove the tables usually used for cafeteria purposes, it has heretofore been an unnecessarily long and sometimes difficult task. Tables, as such, are unhandy articles of furniture to store, and take up almost as much space stored as when spread out. Also breakage of the legs which, when extended, are especially vulnerable to the weight of other tables if piled on one another, and the strain of handling. This weakening of the legs makes them unfit for the hard service which they must undergo in the usual cafeteria. This harsh treatment, plus the constant moving of the tables in clearing the cafeteria for other purposes, makes the usual folding table of little or no use.

It is the object of this invention to present a table having folding legs, which when folded may be stored with others of its kind in a compact space and which can be handled without danger of damage to the piece of furniture.

It is the object of this invention to provide a table having folding legs and protecting sides which thoroughly protect said legs when in folded position.

It is the object of this invention to provide a table having folding legs which when in set up position is braced to provide against any relative movement between the legs and table surface.

It is the object of this invention to provide means for adjusting the brace so that regardless of outside wear or shrinkage due to internal stress the table will be thoroughly braced against relative movement between the legs and the table surface.

It is a further object of this invention to provide side pieces extending downward from the table surface which will protect the legs when in folded position.

It is a further object of the present invention to provide means for locking the supporting parts in folded position.

It is a further object to provide means for locking all the parts of the table in folded position with a single locking means.

It is a further object to provide a table which when in folded position presents no projections beyond its table surface on one side and a plane

formed by the lower edges of the protecting side pieces.

It is a further object to provide a table which may be set up or dismantled without the use of any tools.

This invention is illustrated in the accompanying drawing in which:

Fig. 1 is a side view of the table set up.

Fig. 2 is an end view of the table.

Fig. 3 is a bottom plan view of the table with the legs folded and the other parts secured in position for storing.

Fig. 4 is a detailed action showing the bracing means for supporting the table legs in set up position.

Fig. 5 is a section, with parts omitted, showing the brace support and pin holding means.

Fig. 6 is a section with parts omitted showing the brace lock and wedge compartment.

As illustrated the table has a surface 1 having downwardly projecting side pieces 2, legs 3 and 4 and a brace 5.

The table in a set up position occupies a space 8 ft. x 2 ft. x 2 1/2 ft.; in folded position occupies 8 ft. x 2 ft. x 1 1/3 ft., a ratio of about 8:1. The relationship of its width to its length permits the table to be grouped to form a platform or the like.

The legs 3 and 4 are secured to the under side 30 of the table surface by hinges 6 and 7 arranged so that the edges 8 and 9 of the legs firmly abut the underside of the table surface when in set up position. The legs are tapered to a bottom width just sufficiently small to fit inside the side pieces 2 and terminating in feet 10. A rectangular opening 11 is made in each of the legs to receive the brace 5.

The brace 5 is a single sturdy plank, notched adjacent each end at 12 and having a central hole 13 and holes 14 in said notches.

Wedges 15 and 16 are used in conjunction with the brace to support the table in set up position. Secured to the under side of the table are brace supports 17, a wedge receiving box 18, locking pins 19 and a bolt 20. A thumb screw 21 threaded into a seated nut 22 is part of the leg construction.

For purposes of illustration, consider the table in folded position as shown in Fig. 3. To set 50 up the table it is only necessary to slide the bolt 20 from the hole 13 in the brace 5. Slide the brace toward the center of the table releasing the brace 5 from the pins 19. The legs are swung on hinges 6 and 7 to supporting position, 55 the edges 8 and 9 limiting the movement of said

legs and also positioning said legs vertically or at right angles to the table surface. The brace is then placed in the openings 11, the notches 12 being uppermost. Wedges 15 and 16 are removed from the box 18 being uncovered by removal of the brace. These wedges are pushed by hand below the brace and into the opening 11, forcing the notched portion of the brace up on the leg as shown at 23 in Fig. 4. Screws 21, which are not shown applied in Fig. 3, are threaded into seated nut 22 and bearing against the wedge firmly locks the table in set up position.

It is only necessary to reverse the process to dismantle the table for storing. When in dismantled condition the thumb screws may, of course, be left in the legs and the brace held only by the bolt and the pins 19 prevents movement of the folded legs and loss of the wedge pieces.

The table has been illustrated as having only two legs but, of course, could be made with three, four or any desired number. This table could be easily shipped and when received would not have to be assembled by a carpenter but could in a few minutes be set up for use.

What is claimed is:

1. A table comprising a table top surface, protecting sides extending downward from said surface, legs hinged to the underside of said surface, a brace, supporting blocks carried on the under side of said table surface, locking pins on said protecting sides, said brace engaging said blocks

and said pins to hold said legs in folded position, and means for locking said brace in holding position.

2. A table comprising a table top surface, protecting sides extending downward from said surface, legs hinged to the under side of said surface and adapted to be folded to be within said protecting sides, a brace formed with holes at either end, brace supports secured to the under side of said surface, pins projecting from one of said protecting sides and receivable in said brace holes, a housing compartment carried on the under side of said surface and adapted to be covered by said brace and means for locking said brace on said brace supports and in cooperation with said pins to cover said housing compartment and secure said legs in folded position.
3. A table comprising a table top surface, protecting sides extending downward from said surface, legs hinged to the underside of said surface and movable to folded position substantially parallel to and in contact with the underside of said table top surface, an open compartment attached to the underside of said table top surface and adapted to house movable parts, a separable brace for securing said legs in said folded position, said brace extending over and forming a cover for said open compartment when in said leg securing position and means for locking said brace in said leg securing and compartment covering position.
